UNITED STATES PATENT OFFICE

105,946

DESIGN FOR AN ADDING MACHINE

Max Garbell, Chicago, Ill., assignor to Victor Adding Machine Company, Chicago, Ill., a corporation of Delaware

Application April 17, 1937, Serial No. 68,844

Term of patent 14 years

To all whom it may concern:

Be it known that I, Max Garbell, a citizen of the United States of America and a resident of Chicago, Cook County, Illinois, have invented a new, original, and ornamental Design for an Adding Machine, of which the following is a specification, reference being had to the accompanying drawing, forming a part thereof.

ture of which is the shape of the cover plate for the platen shown in full lines and its placement on the adding machine.

I claim:

The ornamental design for an adding machine substantially as shown and described.

MAX GARBELL.
